UNITED STATES PATENT OFFICE

JOHN LOGIE BAIRD, OF LONDON, ENGLAND, ASSIGNOR TO TELEVISION LIMITED, OF LONDON, ENGLAND, A BRITISH COMPANY

TELEVISION AND LIKE SYSTEM

Application filed October 7, 1927, Serial No. 224,710, and in Great Britain October 15, 1926.

This invention is for improvements in or relating to television and like systems, and has for its object to provide an improved method and apparatus for the process or step of exploration which is used in such systems.

5 The invention relates to that type of system in which an image at the transmitting station is traversed relatively to a light-sensitive cell so as to expose in succession all parts of the image to the cell, and to the similar method 10 and apparatus at the receiving station whereby an image is reconstituted by an inversion of the exploring process. A traversal is effected by moving the image across the cell so that the latter scans a narrow band of the 15 image. The image is explored by effecting a series of traversals by shifting the cell or the image laterally a distance equal to the width of the band after each traversal, this process 20 being repeated until the whole area of the image has been explored in a series of parallel bands. It will further be understood that the movements of the image and cell are merely relative movements, and in some cases the 25 movement may be only a virtual one, as for example when exposing a stationary image to a stationary cell through a series of holes in a rotating disc, each hole exposing by its movement a different band of the image.

30 Heretofore such exploration has been carried out by successive traversals which were all alike in direction and sense, but according to the present invention different traversals are made in different directions.

35 This invention also comprises a method of exploration wherein either or each component of the traversing movement is reversed in direction in different traversals.

According to yet another feature of this 40 invention, the inclination to a datum line, such for example as an edge of the picture, of either or each component of the traversing movement, is changed for different traversals; it may, for example, be changed for 45 each successive traversal.

This invention also covers in television or 45 like systems for transmitting pictures and the like, the simultaneous superimposition of images produced by explorations in different directions. Thus, for example, two complete

images produced by explorations in different directions may be superimposed one on the other, or if the bands of one traversal are parallel with the bands of another traversal, each traversal may supply alternate bands, 55 the two sets of bands being intercalated with one another to produce a complete image.

This invention also comprises various constructional forms of exploring device for carrying out the method hereinbefore set 60 forth.

In the accompanying drawings, which are purely diagrammatic, each figure represents a particular form of exploring device.

The invention may be applied to various 65 types of exploring devices, such for example as a rotating disc with holes in it, which holes expose a small portion of the stationary image whilst they are opposite to it; or the slotted discs type of exploring device; or a 70 rotating disc having a series of lenses each of which projects an image and sweeps it across the light-sensitive cell; or other equivalent arrangements with moving bands, rotating mirror polyhedrons, concave mirrors, 75 or combinations of such devices.

For simplicity in illustrations, Figures 1 to 4 show various constructions of the rotatable disc with holes type of exploring device, but it will be appreciated that these 80 drawings would equally well represent the rotating disc with lenses.

Figures 5 to 9 show modified constructions of exploring discs in which straight slots, spirally arranged slots or holes (or lenses) 85 are used either alone or in combination, for periodically reversing the direction of traversal;

Figure 10 illustrates diagrammatically the direction of traversal effected by certain of 90 the modified forms of scanning device, particularly that illustrated in Figure 7 of the drawings.

In Figure 1, 10 represents a disc mounted on a shaft 11 so as to be rotatable at an appropriate speed. This disc has two sets of holes in it arranged in spirals of opposite pitch. One set of holes, commencing with that indicated at 12, which is at the greatest distance from the shaft 11, lies on a spiral 100

indicated by the line 13 which extends half-way round the disc, so that the hole 14 is the nearest of them to the shaft 11. The second set of holes, arranged from 14 round the remainder of the disc to the hole 12, lies on a spiral indicated by the line 15 which is of opposite pitch to the spiral 13. Assuming that the disc is rotating in the direction indicated by the arrow 16, and that the image 10 which is to be explored is at 17, the spiral 13 of holes gives a series of bands of which the length of the bands is in the direction of the arrow 18, and the successive bands are spaced from one another in the direction of the arrow 19. That is to say, the two components of the exploration by the spiral 13 are in the directions 18, 19 respectively.

The spiral 15 gives bands of which the lengths are in the direction of the arrow 18 20 but the bands are spaced apart successively in the direction of the arrow 20 which is opposite to that of the arrow 19, or in other words, the spiral 15 has the direction of one of its components reversed with respect to 25 that of the spiral 13, and since each spiral gives a complete traversal of the image, the successive traversals are in opposite directions.

Figure 2 shows a modification in which 30 each of the spiral sets of holes extends completely around the disc instead of only half-way round it. One spiral starting from the hole 21 extends in an anti-clockwise direction as indicated by the line 22 to the hole 23, and the other spiral extends from the hole 21 in a clockwise direction, as indicated by the line 24. The holes for the two spirals are intercalated in order that the single light-sensitive cell can explore the whole picture; 40 it will be seen that when the disc is rotating in the direction indicated by the arrow 25, the spiral 22 provides a series of bands whose length lies in the direction indicated by the arrow 26 and the bands appear successively 45 in the direction of the arrow 27. The spiral 24, on the other hand, provides bands whose length is in the direction of the arrow 26, but they appear successively in the direction of the arrow 28. Moreover, the bands appear 50 alternately, first one on the right, then one on the left, the first image being built up from the right towards the left and the second from the left towards the right. Each 55 image may be complete in itself and the two images simultaneously superposed, or each spiral may provide only alternate bands, so that the two sets of bands together constitute a complete image or picture.

Figure 3 shows a modification in which a 60 two-part spiral 29, 30 similar to the arrangement shown in Figure 1, is associated with a second similar spiral 31, 32, being in effect a combination of the constructions of Figures 1 and 2.

65 It will be seen that when the two spirals

of opposite pitch are arranged on a single disc in the manner shown in Figures 1, 2 and 3, the lengths of the bands produced by the two spirals always lie in the same direction, and only the second component of the exploration movement is altered. By arranging the spirals on eccentric discs as shown in Figure 4, the directions of the length of the bands can be altered. In Figure 4 a disc 33 rotating in the direction indicated by the arrow 34 has a spiral of holes 35 extending half-way round it, and this disc gives an exploration in which the lengths of the bands lie in the direction of the arrow 36 and the successive bands follow one another in the direction of the arrow 37. A second disc 38 with a similar spiral of holes 39 is arranged to rotate about another axis in the direction of the arrow 40, and this disc gives an exploration in which the length of the bands is in the direction of the arrow 41, and the successive bands follow one another in the direction of the arrow 42. The length of the second set of bands is therefore inclined to, and in the arrangement illustrated is substantially at right-angles to, the length of the bands of the first. By reversing the direction of rotation of the disc 38, it will be appreciated that the arrow 42 indicating the successive spacing of the second set of bands can also be reversed. Since the explorations provided by the two discs 33, 38 have to follow one another successively, each disc is cut away over substantially half its circumference, or is slotted as at 43, 44 in order to expose the image to the other disc.

Exploring devices are known comprising two radially slotted rotatable discs rotating about different axes so positioned that the slots cross one another in front of the image. One of the discs is made to rotate comparatively slowly with respect to the other, and its slots define the direction of the length of the bands produced by this method of exploration. The present invention can be applied to this type of exploring device by arranging the slots on the slower-moving disc in a zig-zag or other formation such that they are differently inclined to some datum line, such for example as the edge of the picture. Such an arrangement is illustrated in Figure 5 in which the disc 45 is provided with a series of radial slots 46 and the disc 47 is provided with a series of slots arranged in zig-zag formation as shown at 48. Whilst one of the slots 48 is moving a distance equal to its width, one of the slots 46 sweeps across it, thereby tracing out one band or strip of the image. The next slot 46 traces out the next succeeding band, and so on, until one traversal is completed. The next slot 48 then comes into operation and defines the series of bands for the next traversal, and since the second slot 48 lies at an angle to the first slot 48, the successive explorations take place in different directions.

Figure 6 illustrates yet another arrangement of exploring device comprising two discs 49, 50. Each disc is provided with two sets of spiral holes indicated by the lines 51, 52 and 53, 54 respectively, and each disc also carries a spirally arranged set of slots adapted to expose the holes on the other disc when these holes in turn pass across the area 55 defining the picture to be transmitted. The two discs rotate in the same direction about parallel axes, so that the holes on one disc pass downwards across this area and the holes on the other disc pass upwards across it thereby exploring the bands in opposite directions. With the arrangement illustrated each disc explores alternate bands of the picture, so that the two sets of bands together make up the complete picture. It will be appreciated that the arrangement of the holes and slots must be such as to expose only one hole at any instant unless provision is made for the simultaneous exploration of different sections of the picture simultaneously, by means of an appropriate number of light-sensitive cells.

Figure 7 shows an arrangement of two discs each with its own spiral of holes and a set of slots in each disc to co-operate with the holes in the other disc, the arrangement being such that the bands explored by the one disc are at right-angles to the bands explored by the other disc. With this arrangement the distortion is reduced to a minimum and the maximum amount of detail is shown in the picture.

Figure 7 illustrates diagrammatically the path of the scanning lines obtained by the use of the device illustrated in Fig. 7. It will be noted that the exploration is effected first in one direction and then in the other by alternate discs, the successive directions of traversal being indicated by the reference characters 58 to 63 inclusive. By altering the relative positions of the apertures and slots in the two discs the succession of the various traversing lines may be correspondingly altered, and it is understood that the invention is not limited to the precise method of exploration illustrated in Fig. 10.

As above stated, lensed holes may be substituted for the simple openings in the disc of the exploring device, and Figure 8 shows a construction in which two discs are each provided with a spiral of lenses, the arrangement being such that the picture is explored in vertical bands by one of the discs and horizontal bands by the other disc.

It also lies within the scope of this invention to effect the exploration in two different directions, by using two separate light-sensitive or photoelectric cells, one for each direction of exploration. One example of this arrangement is illustrated diagrammatically in Figure 9 in which two separate images of the object are used one for each exploring disc.

The two images are preferably produced as closely side by side as possible so that they will be substantially identical with one another, and the two exploring discs indicated at 56, 57 are provided with a spiral of holes or lenses so as respectively to explore the two images in bands at right-angles to one another. With this arrangement the two explorations can proceed simultaneously, that is to say, during the exploring of a horizontal band on one image, a vertical band can be simultaneously explored on the other image. The two images are simultaneously transmitted to the receiving station and there superimposed one upon the other.

It will be appreciated that mirrors may be used instead of holes or lenses on the discs as is usual with this type of exploring device.

In all the constructions embodying two discs which are required to rotate in the same direction, it is desirable that these discs should rotate in absolute synchronism with one another and this is preferably effected by directly coupling them together as for example by means of two coupling-rods on cranks which are inclined, say, at right-angles to one another; an alternative method of connecting them is to use a single crank on each disc and a third idler crank which is displaced from the line joining the two shafts and coupling all three cranks by means of a single rigid triangular connecting rod. This construction provides a connection which has no dead centre.

It will be appreciated that this exploring device can be used for exploring a picture by means of a light-sensitive cell or cells at the transmitting station, and can also be used for reconstituting an image on the picture at the receiving station.

This invention also covers the use of a disc having a zig-zag arrangement of slots as shown at 47, 48 at the receiving station of a television system, as a "spotting device". If a spot of light be cast on the object or view which is being transmitted, and the receiving station be provided with a disc similar to the disc 47 instead of or in addition to the usual exploring device, the spot of light will be reproduced as a luminous cross which can be more easily located than an image of the spot of light. This arrangement is of value for military purposes, particularly when used in combination with a beam of light which is outside the visible spectrum.

I claim:-

1. In television apparatus, the combination with a light sensitive device, of means for exploring an object by said device in such manner that successive traversals are made in directions which are at right angles.

2. In television apparatus, the combination with a light sensitive device, of means for scanning an object by said device, said means comprising a pair of rotatable discs, one of

said discs serving to explore the object by a series of traversals in one direction, and the other disc serving to explore the object by a series of traversals in a direction at right angles thereto.

5. In television apparatus, the combination with a light sensitive device, of means for scanning an object by said device, said means comprising a pair of rotatable discs, each provided with a series of apertures so disposed that successive traversals of the object are made by alternate discs.

10. In television apparatus, the combination with a light sensitive device, of means for scanning an object by said device, said means comprising a pair of rotatable discs, each provided with a series of apertures so disposed that successive traversals of the object are made by alternate discs, and are angularly related in direction.

15. In television apparatus, a pair of rotatable discs for exploring an object, each disc being provided with a series of spirally disposed apertures, said discs being so positioned 20 with relation to each other as to produce periodic alignment of certain of the apertures in the two discs.

25. In television apparatus, a pair of rotatable discs for exploring an object, each disc being provided with a series of spirally disposed apertures, the axes of the discs being spaced apart whereby one disc effects traversals of the object in a direction at an angle to the traversals effected by the other.

30. In television apparatus, a pair of rotatable discs for exploring an object, each disc being provided with a series of spirally disposed apertures, the axes of the discs being so related to the optical axis of the system 35 that the apertures in one disc traverse the object in a direction substantially at right angles to those of the other disc.

35. In television apparatus, a pair of rotatable discs for exploring an object, each disc being provided with a series of spirally disposed apertures, the axes of the discs being so related to the optical axis of the system 40 that the apertures in one disc traverse the object in a direction substantially at right angles to those of the other disc, successive traversals being effected by alternate discs.

45. In television apparatus, a pair of rotatable discs, each disc being provided with a series of spirally disposed apertures, and a 50 series of slots, said discs being so disposed with relation to each other as to produce periodic alignment of the apertures in one disc with the slots in the other disc.

55. In television apparatus, a pair of discs, each disc being provided with a series of spirally disposed apertures, and a series of 60 slots, said apertures and slots being alternately arranged in each disc.

65. In television apparatus, a pair of rotatable discs for exploring an object, each

disc being provided with a series of spirally disposed apertures, the axes of the discs being so related to the optical axis of the system that the apertures in one disc traverse the object in a direction substantially at right angles to those of the other disc, successive traversals being effected by alternate discs, and a series of slots in each disc alternating with the apertures, each slot being angularly arranged with respect to the radius of the disc at that point, whereby a beam of light passing through an aperture on one disc during traversal may pass through a slot in the other disc.

70. In testimony whereof I affix my signature. 75
